EMIL RAFFLOER, OF DUISBERG, GERMANY.

APPARATUS FOR COKING SOLID FUEL.

Application filed April 1, 1925. Serial No. 19,754.

My invention relates to improvements in apparatus for coking solid fuel such as coal or brown-coal at low temperature, and more particularly in an oven in which the solid fuel is coked within a rotary drum provided internally with longitudinal chambers for the reception of the fuel and adapted to be externally heated. In rotary ovens of this type a roller has been provided internally of the oven for compressing the coal confined within the said chambers, and while slowly rotating the drum the coal is successively pressed into the successive chambers from one end thereof by means of a plunger having reciprocating movement in the direction of the said chambers and adapted when charging a chamber to force the finished product therefrom. The object of the improvements is to increase the efficiency of the oven and to render the operation thereof more easy. With these objects in view my invention consists in providing within the rotary drum a tubular roller for compressing the coal confined within the chambers, and providing means for passing the coal to be subjected to the process first through the said tubular roller and towards the charging side of the rotary drum, and thereafter through said chambers. Thereby the coal passed through the said roller is preheated, dried and partly desulfurized, the steam and the hydrogen-sulfide being preferably removed from the roller separately from the vapor developed from said chambers, so that the gas produced by the coking process is comparatively free of steam and sulfur. Further, the chambers receiving the coal are constructed so that they are gradually increased in cross-sectional area from the charging end to the delivery end, and preferably the diameter of the rotary drum is gradually increased from the charging to the delivery end, so that the breadth of the chambers is gradually increased. In lieu of increasing the breadth, or in addition thereto, the radial dimension of the chambers may be increased. In rotary ovens now in use the chambers are open at their inner sides, and ordinarily I intend to adopt the same system. But in some cases I provide

means to cover the chambers at the parts adjacent to the intake ends thereof where the coal is heated and gasification does not yet begin.

By heating and coking, the coal is expanded, and tends to stick to the walls of the chambers. To avoid this, and to facilitate the escape of the gas I prefer to provide the coal filled into the chambers with a hollow space, for which purpose I provide the plunger at its front end with a rod adapted to be extended into the successive chambers and to form a hole therein.

I have found that ordinarily the resistance of the coal moved by the said plunger through the chambers is sufficient to insure compression of the coal, and that in some cases the frictional reaction of the coal is not sufficient to produce a compact coke, and in such cases I provide reaction means at the delivery end of the rotary drum in position for reacting on the coal being compressed by the plunger. Preferably such reaction means consist of a plate located in position for closing the chamber and acted upon by a spring or a weighted body.

Preferably a generator is provided in connection with the coke oven for receiving the coke, gasifying the same, and, in some cases, supplying gas for heating the coke oven. I have found that this combination is particularly effective, because the coke produced in my oven is hard and coherent, so that it is not blown by the air from the generator. By directly supplying the hot coke from the oven to the generator, and heating the oven by means of the gas from the generator, the operation of the plant is made economical.

My improved process is suitable for making bricks from mixtures of solid fuel with granular ore, the bricks thus produced being very hard and coherent, so that they are not broken within the metallurgical furnace.

For the purpose of explaining the invention more in detail an oven has been illustrated in the accompanying drawings, in which the same reference characters have been used in all the views to indicate corresponding parts. In said drawings, Fig. 1, is an elevation showing the plant

including the coke oven and the generator, Fig. 2, is a sectional elevation showing the coke oven, and

Fig. 3, is a section taken on the line 3—3 5 of Fig. 2.

In the example shown in the drawings the plant consists of a rotary coke oven 1 and a generator 2. As appears more particularly from Figs. 2 and 3, the coke oven comprises a cylindrical brick work 32 having a cylinder 10 of iron or steel rotatably mounted therein. Between the brick work and the said cylinder there is a chamber divided by partitions 33, 34 and 35 so as to provide a flue 36 having its inlet at 5 and its outlet at 7, the inlet being connected by a pipe 37 with the gasification chamber of the generator, and the outlet 7 being connected by a pipe 38 with a stack. To the ends of the cylinder 10 rings 39 are secured which are supported on rollers 40, and one of the said rings is formed with gear teeth 27 engaged by a gear wheel 26 secured to a driving shaft 41 by means of which rotary movement is imparted to the cylinder 10.

Internally the cylinder 10 is provided with longitudinal partitions 11 providing chambers 12 adapted to receive the solid fuel to be subjected to the process.

At one end the cylinder 10 is closed by a wall 42 made integral with a funnel 20, an exhaust pipe 21 and a delivery pipe 3, all of the said parts being suitably supported on uprights 43. The opposite end of the cylinder is closed by a plate 44 made integral with a container 45, a funnel 46 opening into the said container and a tubular member 47 communicating with the container 45, the whole of the said parts being supported on uprights 48.

Within the cylinder 10 and at the bottom part thereof there is a tubular roller or conveyor 13 formed at its left hand end with a hub 49 supported on a trunnion 50 projecting from the end wall 42. At its opposite end the roller 13 is made integral with a hub 51 having a shaft 52 secured thereto, which shaft is provided with suitable driving means represented in Fig. 2 by a gear wheel 53. The shaft 52 is suitably supported in the end plate 44 and the wall of the casing 45. Internally the roller 13 is provided with a conveyor 19 for moving the solid fuel from the intake or left hand end 55 of the roller 13 to the right hand end thereof.

The funnel 20 and the exhaust pipe 21 open into the roller 13, the object of the funnel being to supply fresh fuel to the roller 13, and the object of the pipe 21 being to remove vapor such as steam and hydrogen-sulfide therefrom. The delivery end of the roller 13 opens into the container 45 where the coal is deposited. In addition, solid fuel may be supplied to the container 45

through the funnel 23 after opening a valve 22.

The tubular member 47 is in alignment with the chambers 12 passing upon rotation of the cylinder 10 in front thereof, and the said tubular member has a plunger 14 mounted therein, which is adapted to be reciprocated by a cam 28 keyed to a shaft 54. Preferably a rod 17 is provided at the inner end of the plunger 14. The object of the plunger 14 is to force the fuel from the container 45 into the chambers 12 which are successively brought in line with the tubular member 47. Thus the fuel is compressed within the chambers 12, the rod 17 providing a hollow space 18 within the fuel being advanced through the chambers 12. The compressed and coked fuel is delivered into the tubular member 3. Ordinarily the frictional resistance of the fuel is sufficient to insure sufficient compression by the plunger 14. But in some cases I provide a gate 24 at the delivery end of the tubular member 3, which gate is automatically and yieldingly pressed towards the member 3 for example by means of a weighted body 25.

In the preferred construction I provide the chambers 12 with cross-sections which are gradually increased from the right hand or inlet end to the left hand or delivery end. As shown the cylinder 10 is increased in diameter from the intake end to the delivery end, so that the height of the partitions 11 and the breadth of the chambers at the outer circumference is gradually increased.

In some cases I provide a cylinder 29 at the inlet end of the cylinder 10 for covering the chambers 12 at their inner sides. The length of the said cylinder is such that the chambers are closed only at the part of their length where the fuel is heated, and coking and gasification does not yet take place.

In ovens of the kind referred to the solid fuel is heated only so far that the fuel is not perfectly coked and is delivered in a state which I shall describe as semi-coked, the fuel being heated in the chambers 12 at a temperature of about 500° C.

The operation of the coke oven is as follows: The solid fuel is supplied to the oven through the funnel 20 from which it is discharged into the tubular roller 13, while intermittent rotary movement is imparted to the said roller 13 and the cylinder 10. The helical vanes 19 provided within the roller 13 convey the fuel towards the container 45, so that the fuel is dried and desulfurized, the steam and hydrogen-sulfide escaping through the exhaust pipe 21. From the container 45 the fuel is intermittently forced by the reciprocating plunger 14 into the chambers 12 and through the same towards the delivery pipe 3, and by the fric-

tional resistance and, in some cases, by the reaction of the yielding gate 24 the coal is compressed, so that it is delivered from the pipe 3 in the form of hard and coherent blocks. The coke delivered from the pipe 3 may be shipped to a place of further use, or it may be directly discharged into a funnel 4 of the generator 2 for being directly gasified therein. The gas produced with-
10 in the generator is in part conveyed through the pipe 37 and to the flue 36, where it is used for drying and preheating the coal within the roller 13 and degasifying the same within the chambers 12. The gas not used for heating purposes is delivered through a pipe 6 and conveyed to a place of further use. The delivery of the gas to the pipes 6 and 37 is controlled by valves 56 and 57. The gas produced from the
15 coal within the chambers 12 is discharged through the pipe 8.

In such cases in which the roller 13 is out of use the fuel may be directly supplied to the container 45 through the funnel 23. Ordinarily the said funnel is closed by a
20 gate 22.

I claim:

1. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers
30 which are open to the inside of the drum; a rotary tubular roller arranged longitudinally within the said drum and free from said partitions in such position as to cover the open parts of the inner sides of the low-
35 ermost of said chambers, said roller being rotatable on an axis substantially parallel to but below the axis of rotation of said drum; means to rotate the drum so as to bring suc-
40 cessively the different chambers below the said roller; means to pass matter to be coked first through the said roller and then through the said chambers; and means to heat the said matter whilst passing through the roller and through the chambers.

2. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary tubular roller arranged longitudinally within the said drum and free from
50 said partitions in such position as to cover the open parts of the inner sides of the low-
55 ermost of said chambers, said roller being rotatable on an axis substantially parallel to but below the axis of rotation of said drum; means to rotate the drum so as to bring suc-
60 cessively the different chambers below the said roller; means to pass matter to be coked first through the said roller and then through the said chambers; means for sup-
65 plying solid matter to the chambers and means, separate from the second mentioned means, for supplying solid matter to the said roller; and means to heat the said matter whilst passing through the roller and through the chambers.

3. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary tubular roller arranged longitudinally within the said drum and free from said partitions in such position as to cover the open parts of the inner sides of the low-
70 ermost of said chambers, said roller being rotatable on an axis substantially parallel to but below the axis of rotation of said drum; means to heat the said matter whilst passing through the roller and through the chambers.

3. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary tubular roller arranged longitudinally within the said drum and free from said partitions in such position as to cover the open parts of the inner sides of the low-
75 ermost of said chambers, said roller being rotatable on an axis substantially parallel to but below the axis of rotation of said drum; means to rotate the drum so as to bring suc-
80 cessively the different chambers below the said roller; supplying means at one end of the drum for supplying matter to be coked
85 through the said roller to the before mentioned supplying means; and means to heat the said matter whilst passing through the roller and through the chambers.

4. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary tubular roller arranged longitudinally within the said drum and free from said partitions in such position as to cover the open parts of the inner sides of the low-
90 ermost of said chambers, said roller being rotatable on an axis substantially parallel to but below the axis of rotation of said drum; means to rotate the drum so as to bring suc-
95 cessively the different chambers below the said roller; supplying means at one end of the drum for supplying matter to be coked
100 through the said roller to the before mentioned supplying means; and means to heat the said matter whilst passing through the roller and through the chambers.

4. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary tubular roller arranged longitudinally within the said drum and free from said partitions in such position as to cover the open parts of the inner sides of the low-
105 ermost of said chambers, said roller being rotatable on an axis substantially parallel to but below the axis of rotation of said drum; means to rotate the drum so as to bring suc-
110 cessively the different chambers below the said roller; supplying means at one end of the drum for supplying matter to be coked
115 through the said roller to the before mentioned supplying means; and means to heat the said matter whilst passing through the roller and through the chambers.

5. A coke oven, including in combination; an elongated rotary drum having its axis of rotation longitudinal thereof and substantially horizontal and having longitudinal partitions therein extending inwardly from
120

the longitudinal wall of said drum so as to form channel-like longitudinal chambers which are open to the inside of the drum; a rotary tubular roller arranged longitudinally within the said drum and free from said partitions in such position as to cover the open parts of the inner sides of the lowermost of said chambers, said roller being rotatable on an axis substantially parallel to but below the axis of rotation of said drum; means to rotate the drum so as to bring successively the different chambers below the said roller; means to pass matter to be coked first through the said roller and then through the said chambers; means to heat the said matter whilst passing through the roller and through the chambers; and separate discharge conduits for the gases and vapors extracted from the roller and from the drum respectively.

6. A coke oven, including in combination;
an elongated tapered rotary drum having its
axis of rotation longitudinal thereof and
substantially horizontal and having longi-
tudinal partitions therein extending inward-
ly from the longitudinal wall of said drum,
said partitions being of increasing height so
as to form channel-like longitudinal cham-
bers of increasing cross sectional area from
one end to the other end which chambers are
open to the inside of the drum; means to
press the matter to be coked through the said
chambers from the end of smaller cross sec-
tional area to the end of larger cross sec-
tional area; means to rotate the said drum
and means to heat the matter moving
through the said chambers.

7. A coke oven, including in combination;
an elongated rotary drum having its axis of
rotation longitudinal thereof and substan-
tially horizontal and increasing in diameter
from one end to the other end and having
longitudinal partitions therin extending in-
wardly from the longitudinal wall of said
drum, said partitions being shaped to form
channel-like longitudinal chambers of in-
creasing cross sectional area from one end to
the other end and which chambers are open
to the inside of the drum; means to press
50 the matter to be coked through the said
chambers from the end of smaller cross sec-
tional area to the end of larger cross sec-
tional area; means to rotate the said drum;
and means to heat the matter moving
55 through the said chambers.

55 through the said drum.

8. A coke oven, including in combination; a drum mounted for rotation on a horizontal axis and having inner longitudinal partitions extending radially from its wall so as to form channel-like longitudinal chambers which are open to the inside of the drum; a rotary tubular roller arranged longitudinally and eccentrically within the said drum in such position as to cover the open parts of the inner sides of the lowermost of said

chambers; means to rotate the drum so as to bring successively the different chambers below the said roller; a container adjacent one end of the drum to receive material therefrom; a plunger adapted for successively pressing the material to be coked from said container into the said chambers and formed at its end with a portion of reduced cross section, making longitudinal holes in the matter being pressed; means to reciprocate the said plunger in and out of the said chambers; and means to heat the said matter whilst passing through the roller and through the chambers.

9. A coke oven, including in combination; 80
a drum mounted for rotation on a horizontal
axis and having inner longitudinal parti-
tions extending radially from its wall so as
to form channel-like longitudinal chambers
which are open to the inside of the drum; a 85
rotary tubular roller arranged longitudi-
nally and eccentrically within the said drum
in such position as to cover the open parts
of the inner sides of the lowermost of said 90
chambers; means to rotate the drum so as to
bring successively the different chambers be-
low the said roller; means to press the mat-
ter to be coked through the chambers; means
to partially resist the delivery of the matter 95
from the ends of the chambers opposite to
the said matter pressing means; and means
to heat the matter moving through the said
chambers.

10. A coke oven, including in combination; a drum mounted for rotation on a horizontal axis and having inner longitudinal partitions extending radially from its wall so as to form channel-like longitudinal chambers which are open to the inside of the drum; a rotary roller arranged longitudinally within the said drum and free from said partitions in such position as to cover the open parts of the inner sides of the lowermost of said chambers, said roller being rotatable on an axis substantially parallel to but below the axis of rotation of said drum; means to rotate the drum so as to bring successively the different chambers below the said roller; means to pass the matter to be coked through the said chambers; and means to heat the matter whilst passing through the said chambers.

11. A coke oven, including in combination; an elongated rotary drum having its axis of rotation longitudinal thereof and substantially horizontal and having longitudinal partitions therein extending inwardly from the longitudinal wall of said drum so as to form channel-like longitudinal chambers which are open to the inside of the drum; a rotary roller arranged longitudinally within the said drum and free from said partitions in such position as to cover the open parts of the inner sides of the lowermost of said chambers, said roller 130

being rotatable on an axis substantially parallel to but below the axis of rotation of said drum; a cylindrical roller within the drum for covering the open sides of said chambers through a portion of the length of the drum; means to rotate the drum so as to bring successively the different chambers below the said roller; means to pass matter to be coked through the said chambers; and means to heat the matter whilst passing 10 through the said chambers.

In testimony whereof I hereunto affix my signature.

EMIL RAFFLOER.
